SHEET METAL CAP

Henry V. Rau, Amityville, N. Y., assignor to
 Edwin B. Stimpson Company, Brooklyn, N. Y.,
 a corporation of New York

Application March 10, 1933, Serial No. 660,211

4 Claims. (Cl. 24—220)

The present invention relates to a sheet metal article and more especially a sheet metal cap.

Heretofore in the art, it has been deemed impossible by metal drawing and forming dies to make a non-circular sheet metal cap with a continuous inturned reenforcing edge and fastener engaging members forming a non-circular opening in the back of the cap. The practice heretofore has been to provide a blank having a number of arms extending from the body of the blank and then rolling over the arms to cause edge to edge contact thereof with the ends of the arms cut away to form a circular opening for a fastener socket when the arms were rolled into edge to edge engagement.

The present invention comprises a sheet metal fastener cap of non-circular contour having a back spaced apart from a continuous inturned reinforcement rim with snap socket supports extending from the integral rim. The cap comprising the present invention is more economical to manufacture and is of such sturdy, solid construction as to withstand rough usage far better than caps of the prior art provided with the rolled in fingers.

The present invention also comprises the method of producing the present cap wherein a non-circular shaped blank is drawn into the shape of the outline of the non-circular cap with an upstanding continuous edge which is subjected to a plurality of forming operations that gradually inturns the edge and the socket supporting members with the result that the back of the cap becomes an ornamental member which covers a fastener socket and with the face of the cap comprising an extremely strong rigid construction adapted to be securely locked in place around the fastener socket when the parts are assembled.

It is recognized that the present invention may be carried out in constructions and by methods other than those specifically disclosed herewith. Therefore, the present disclosure is to be understood as illustrative and not in the limiting sense.

Referring to the drawings, Fig. 1 illustrates a blank for an octagonal shaped cap.

Fig. 2 is a perspective view illustrating the drawing operation from the blank shown in Fig. 1.

Fig. 3 is an elevational view of the construction shown in Fig. 2.

Fig. 4 illustrates the first forming operation performed on the shape shown in Fig. 2.

Fig. 5 illustrates the second forming operation.

Fig. 6 is a plan view of the completed octagonal cap at the end of the third forming operation.

Fig. 7 is an elevational view of the cap shown in Fig. 6.

Fig. 8 illustrates the octagonal cap locked in position upon a fastener socket.

Fig. 9 illustrates the blank for an oval shaped cap.

Fig. 10 illustrates the drawing operation on the oval cap.

Fig. 11 illustrates the first forming operation on the shape shown in Fig. 10.

Fig. 12 illustrates the second forming operation.

Fig. 13 illustrates an elevational side view of the finished oval cap.

Fig. 14 illustrates the face of the finished oval cap.

Fig. 15 is a sectional view illustrating the oval cap in position upon a fastener socket.

In accordance with the present invention of making non-cylindrical fastener caps from sheet metal, a blank as illustrated in Fig. 1 is cut from sheet metal, and comprises a body portion 1 provided with octagonal sides 2 and with fastener socket holding arms 4.

Fig. 2 illustrates the first step of manufacture which is a drawing operation. This operation shapes the blank into a cap having a back 5 with an upstanding octagonal rim 6, and with the arms 4 positioned substantially parallel to the axis of the rim 6.

Fig. 4 illustrates the second operation on the octagonal shaped blank in that the upper end of the rim is bent inward to begin to form a flange 7 and the arms 4 are slightly inclined inwardly toward each other.

Fig. 5 illustrates the third forming operation in which the arms 4 are further bent inward and the rim portion 7 is further depressed.

Fig. 6 illustrates the face of the finished cap after the third forming operation, in which the rim 7 has been set to final position and the arms 4 are positioned opposing each other in such manner that the segmental faces 8 on the arms form locking faces against which the fastener socket is adapted to be set.

The opening 9 in the face formed by the rim 7 and the arms 4 is a distorted hour-glass shape, the general outline of which, except for the interruption by the arms 4, is similar to the octagonal outline of the button.

Fig. 9 illustrates the steps to form an oval type button. The blank 10 in this case is formed somewhat of the shape of a violin. This blank is then subjected to a drawing operation which produces an oval shaped back 11 extending into

a rim 12 having cut-outs 14 and 15 in the upper edge thereof. The second operation (Fig. 11) after making the blank, is a forming operation turns in the edges of the rim 12 in such manner that the edges of the rim are directed toward each other and the sides of the rim 12 are made somewhat oval.

5 The third operation (Fig. 12) after making the blank, is also a forming operation continues to round the sides 12 and brings the edges 14 and 15 in a more opposed position.

10 The final operation Figs. 13 and 14 which is also a forming operation, somewhat flattens the face of the cap so that the cut-outs 14 and 15 are now 15 opposed to each other to comprise a locking recess to hold a fastener socket, and the side wall 12 is blended into the back 11 to form an oval rounded surface. The opening 16 is somewhat like a double edged keyhole opening which generally 20 conforms to the outline of the cap with the exception of the enlargement to receive the fastener socket.

25 The operations specified to produce the caps described may be broadly stated to comprise a blanking step to form the flat blank from sheet metal, and a drawing step, followed by a plurality of forming steps. These several steps are preferably performed in a multiple die press where in 30 between each operation of the press, the work moves progressively step by step from one die to the next until all of the dies are filled and are operating simultaneously to carry out all operations to complete a cap. When all dies are filled and sheet metal stock is being fed into the press, 35 each operation of the press results in the discharge from the press of a completed cap.

Fig. 8 shows the octagonal cap set over a fastener 17 which is mounted through material such as leather or other material 18 and with the head 40 19 of the socket expanded within the opening 8 in the octagonal cap to lock the cap in place as an ornamental cover for the fastener socket.

Fig. 15 illustrates a cross-section showing the oval-shaped cap set over a socket 17 with the head

of the socket 19 expanded within the cap in the same manner as the octagonal cap is illustrated in Fig. 8.

5 The present invention results in a strong, rigid non-circular cover cap for fasteners, which cover cap comprises one continuous shaped piece of sheet metal without any breaks in the sheet metal such as heretofore been provided in the art. The present cap, therefore, is not only economical to manufacture, but is very rigid in construction so 10 as to support the operation of expanding the socket within the cap to lock the cap securely in position.

15 What I claim is:

1. As an article of manufacture, a sheet metal cap of non-circular form comprising a back, an edge portion, an inturned rim having substantially the non-circular outline of the adjacent edge portion, and cap securing members extending inwardly from said rim.

20 2. A sheet metal cap of non-circular form comprising a back, an inturned rim formed of a continuous metal to provide a hollow cap member, said rim and said back being made of one continuous piece of metal, and fastener securing 25 means carried by said rim.

3. A sheet metal cap of non-circular form comprising a back, and an inturned non-circular reinforcing rim of continuous unbroken metal substantially parallel to said back, and means 30 extending from said rim adapted to enclose and interlock with a fastener socket, said rim and said back being made of one continuous piece of metal.

4. A sheet metal cap of non-circular outline 35 comprising a continuous member having an inturned continuous metal rim spaced from the back to form a hollow enclosing cap, and means provided in said rim to centrally locate a fastener socket within said hollow cap and to 40 interlock with said socket to retain said cap in position over said socket.

HENRY V. RAU.
